ELECTRICAL CONTACT PLUG

Wilmer H. Churchill, Saugus, Mass., assignor to
 United-Carr Fastener Corporation, Cambridge,
 Mass., a corporation of Massachusetts

Application December 10, 1942, Serial No. 468,555

3 Claims. (Cl. 173—363)

The present invention relates to electrical contact plugs of the type commonly used in electrical discharge or thermionic tubes and aims generally to improve the construction of existing plugs of that type.

One type of plug to which the invention particularly relates is called a banana shape plug and comprises a central core with a split sheet metal cage bulged outwardly from the central core so as to make resilient contact with the sockets into which they are inserted. The plug has a portion which is embedded in the molded tube base and is preferably tubular for electrical connection with a wire within the tube. Such cores have previously been screw-machine made parts which are relatively slow and costly of manufacture and must be turned from stock of substantially larger diameter thus necessitating considerable waste of metal.

Heretofore, similar banana type plugs have been made by attaching a cage to a stem having a head, core and intermediate cup-shaped skirted flange. The stem was previously made on a screw machine by turning down the end portion and then boring out the intermediate portion to form the cup-shaped flange. This involved a relatively slow machining operation, as well as a considerable waste of metal in lost turnings, all of which added materially to the cost of making the plug.

My present invention aims to improve the construction of such plugs whereby the necessity for screw-machine made parts is eliminated, thus facilitating the manufacture of the plugs and reducing the cost thereof and eliminating much waste of metal.

Illustrative of my invention, reference is made to the accompanying drawing illustrating a preferred embodiment thereof, and in which:

Fig. 1 is an enlarged sectional view of an improved banana-shaped contact plug according to a preferred form of the invention, the plug being illustrated as embedded in an insulating body and electrically connected to a conducting wire;

Fig. 2 is an enlarged cross-sectional view as taken on the line 2—2 of Fig. 1;

Fig. 3 is a sectional view of the parts composing the contact plug of Fig. 1, the parts being shown in their disassembled position; and

Fig. 4 is a plan view of a metal blank used for making the finger cage.

The invention comprises a banana type electrical contact plug comprising a tubular flanged attaching part, a core and a sheet metal finger

cage having its central portion in contact with substantially the entire area of the outer end of the core and the terminal ends of the fingers crimped or clenched under the flange of the tubular attaching part. According to the invention the attaching part, core and cage are formed separately on conventional machines designed to produce the parts quickly and economically and with a minimum waste of material.

Referring more particularly to the drawing, the contact plug is of three-piece construction comprising an eyelet-attaching part 10, a headed core 15 and a finger cage 18, as is most clearly illustrated in Fig. 3. The attaching part is preferably in the form of a tubular eyelet 10 made on an eyeletting machine and has a reduced shank 11 and an enlarged flanged cupped base 12 at one end thereof. The reduced shank portion 11 is of proper length to extend through an insulating support 12a, as for example the molded base of an electrical discharge tube (not shown), and may be clenched in place and electrically receive a conducting wire 13 positioned within the interior of the tubular shank 11 and secured thereto by suitable means, as for example a soldered connection 14.

The core part is preferably formed as an elongated core 15 having a rounded nose 16 and a head 17 on the opposite end adapted to fit within the cupped flanged base 12. This part may be conveniently formed on a heading machine from a blank of wire stock substantially the diameter of the core 15. Its manufacture thus involves little or no waste of metal and it may be more economically and rapidly produced on a cold-heading machine than on a screw machine as was the case heretofore.

The finger cage 18 is preferably formed from a cross-shaped blank (see Fig. 4) preferably having a solid center 19 and a plurality of radially extending fingers 20. The center portion 19 is preferably cupped to conform to the shape of the core nose 16 to provide a good electrical contact with substantially the entire semi-spherical end of the core. The fingers 20 extend away from the cupped portion 19 in a divergent direction for a substantial distance and then in a convergent direction toward their free ends, providing outwardly spaced bulges or bowed portions spaced from said core 15. The terminal ends of the fingers 20 are flanged outwardly, as at 21, to bear against the under side of the head 17 and to be secured in place by turning the sides of the base flange 12 inwardly under the head 17 and finger flanges 21, as shown in Fig. 1.

The assembled contact plug, as illustrated in Fig. 1, provides a strong efficient plug providing a good electrical conductor from the shank 10 of the eyelet through the core 15 to the nose thereof which has substantial continuous contact with the central portion of the finger cage circumferentially in at least two places, as illustrated in Figs. 1 and 3. The bowed fingers being in engagement with the core 15 at both ends thereof provide yieldable sides for making resilient contact with the sides of the socket member (not shown) into which the plug is inserted.

Advantages of the invention reside in the improved construction of a multiple part banana type contact plug of simple and strong construction which permits manufacture of the component parts expeditiously by rapidly operating heading machines, as distinguished from the slower screw machine.

While I have illustrated and described a preferred embodiment of my invention I do not wish to be limited thereby because the scope of my invention is best defined by the following claims.

I claim:

1. An electrical contact plug comprising an attaching part having an enlarged base formed with a depending annular skirt, a separate core part having an elongated shank and flanged head fitting within said annular skirt and a separate contact cage formed with a cup-shaped central portion embracing and in contact with the end of said core shank, a plurality of outwardly bowed resilient fingers extending from said cupped central portion and circumferentially spaced around said core, the ends of said fingers

being flanged, said annular skirt being inturned under said head and flanged finger ends for securing all of said parts in assembled relation.

2. An electrical contact plug comprising a tubular eyelet having an enlarged base formed with a depending annular skirt, a separate core having an elongated shank and flanged head fitting within said annular skirt and a separate contact cage formed with a cup-shaped central portion embracing and in contact with the end of said core shank, a plurality of outwardly bowed resilient fingers extending from said cupped central portion and circumferentially spaced around said core, the ends of said fingers being flanged, 15 said annular skirt being inturned under said head and flanged finger ends for securing all of said parts in assembled relation.

3. An electrical contact plug comprising a tubular eyelet having a reduced shank adapted 20 to be embedded in a support and receive an electrical conductor, said eyelet having an enlarged base beyond the support and formed with a depending annular skirt, a separate core having an elongated shank and flanged head fitting within 25 said annular skirt and a separate contact cage formed with a cup-shaped central portion embracing and in contact with the end of said core shank, a plurality of outwardly bowed resilient fingers extending from said cupped central portion and circumferentially spaced around said core, the ends of said fingers being flanged, said annular skirt being inturned under said head and flanged finger ends for securing all of said parts in assembled relation.
